WARE

COMBINED TYPEWRITING AND COMPUTING MACHINE

Application filed June 1, 1926. Serial No. 112,797.

This invention relates to a combined typewriting and computing machine, and more particularly to a machine of the Underwood-Hanson type such as shown in the patent to

5 Hanson, No. 1,278,812, of September 10, 1918.

In this machine, a register-rack-bar is provided for each decimal order of a register and each bar carries a series of settable pins representing the digits. The numeral-keys of 10 the typewriter are effective to set pins in the various register-bars representing the numerals of an item to be added or subtracted, and a general operator, having a bar mounted transversely of the register-rack-bars, is 15 subsequently reciprocated in the same direction as the register-rack-bars. During the initial or forward stroke of the actuating cycle, this bar will move in a path adjacent the register-bars and "pick up" the various 20 register-bars by engaging such of the pins as have been set and move the bars in proportion to the various digit values as represented by the pins set therein.

The register-bars are permanently in mesh 25 with a series of register-wheel-pinions which drive a like series of dial-wheels by a pawl-and-ratchet mechanism, the dial-wheels carrying visible numerals on their peripheries. By these means the forward or initial stroke 30 of the register-bars is imparted to the dial-wheels, which thereupon are locked and then the register-bars and the pinions are reset to normal position. A spring-actuated detent is provided for each dial-wheel to align the 35 same. The detents engage modified gears carried by the dial-wheels. Suitable carrying devices are also provided to cooperate with the dial-wheels to carry over the tens values, and these are actuated by the general 40 operator during the returning movement thereof.

When the general operator is reciprocated above a certain speed, the transverse bar will engage the register-pin-bars with considerable impact, the ratchet-driven dial-wheels will move ahead faster than their driving means and the dial-wheel detents will register one or even two units in excess of the right numeral.

50 It is one of the objects of this invention to

provide positive controlling means for the dial-wheels to prevent this momentum movement thereof, so that they cannot over-rotate when actuated at such higher speed as may otherwise be permissible for the machine, since it is well known that the speed at which this machine can be safely operated is largely determined by the means provided to prevent over-rotation of the dial-wheels.

To this end there is provided an actuating device, for the dial-wheel-lock-lever, which functions to positively enter the lock-levers into the tooth-spaces of the dial-wheel gears as these spaces present themselves in succession during the rotation of the dial-wheels, the entering and retracting movement of the lock-levers being so synchronized with the rotation of the dial-wheels that they will at all times prevent movement of the dial-wheels at higher speed than that of the driving pinions, so that the dial-wheels are positively locked in proper position at the end of the stroke.

According to certain features of this invention, there is provided a pawl associated with each dial-wheel, which pawls engage the teeth on the modified gears carried by the dial-wheels. Said pawls are pivotally mounted upon a fixed cross-shaft and are simultaneously vibrated to permit the escapement of one tooth at a time and thus control the speed at which the wheels may be rotated. The means for vibrating the pawls is carried by the general operator and may include a cam-plate having the same number of teeth as the modified gear. The pawls, however, are only vibrated by the general operator during the forward stroke thereof, being spring-held in their ineffective positions during the return-stroke, so as to permit the free rotation of the wheels when the carrying mechanism actuates. To this end there may be provided a one-way pawl which is engaged by the teeth of the plate during the forward stroke of the general operator, the pawl idling over the teeth during the return-stroke of the general operator.

In order to synchronize the movement of the pawls with that of the wheels, there is provided a novel mechanism which is effec-

tive to positively move the pawl-vibrating cam-plate relatively to the general operator. This provides for a very minute adjustment and is an excellent expedient to cheapen the manufacturing cost of such an intricate mechanism, since it permits the use of more liberal manufacturing limits. The plate may be positively locked in place after making the required adjustments.

10 This invention is especially suitable to be used in connection with a machine having means for preventing overcarrying during the return-stroke of the general-operator, such as disclosed in the patent to Thornton, No. 15 1,928,148, dated May 29, 1917, because then the wheels are positively connected at all times with the general operator and are thereby constrained to the movement thereof.

Other features and advantages will hereinafter appear.

In the accompanying drawings,

Figure 1 is a cross-sectional view, in elevation, of an Underwood-Hanson machine showing certain parts thereof in their normal 25 positions.

Figure 2 is a fragmentary plan view of the dial-wheel-locking mechanism.

Figure 3 is a side view showing the pawl-and-ratchet connection between the pin-carrying members and their associated dial-wheels.

Figure 4 is a side view showing the means for adjusting the dial-wheel-locking mechanism relatively to the general operator.

Figure 5 is an operating view showing the 35 position of the locking pawls when the general operator is moved so that the pins in the pin-bars are half a space ahead of the pin-setting bars.

Figure 6 is a similar view showing the pins 40 in the pin-setting bars. In this view the locking pawls are shown in a position to prevent rotation of the wheels.

Figure 7 shows the general operator near its extreme forward position in which the 45 pawls positively prevent movement of the dial-wheels.

Figure 8 is a fragmentary operating view showing the position of the parts during the return stroke of the general operator.

50 This invention is illustrated as applied to a machine of the Underwood-Hanson type. Said machine has as a part of its regular equipment a traveling carriage 10, upon which a platen 11 is rotatably mounted by means of an axle 12. The machine also has a series of character-keys 13 and a row of numeral-keys 14. The numeral-keys 14 are mounted on key-levers 15, rockably mounted at 16, and are effective, by means of bell-crank 17, to swing corresponding type-bars 18. The carriage is letter-spaced by means of a letter-spacing mechanism 20 which is controlled by a universal bar 20^a.

Each of the key-levers 15 is provided with 65 a link 19 which actuates, by means of an asso-

ciated arm 21, a co-operating cross-bar 22 movably mounted on a setting frame 23. Each of the cross-bars 22 is effective to set one of a series of digit-pins 24 on pin-carrying members 25. However, in order that a 70 pin may be set, it is first necessary to advance the pin-carrying member 25 to setting position. To this end, the machine is provided with equipment at the rear of the carriage which consists of selectors 26 which are elevated to effective positions by means of zone-control rollers 27. Said selectors are provided with cams 28, which, when the selectors are in their effective positions, contact with levers 29, rockably mounted at 30. The levers 29 are operatively connected to the pin-carrying members 25 by means of selecting rods 31 and levers 32, pivotally mounted at 33. The forward ends of the levers 32 engage transposing devices 34, which, in turn, are operatively 85 connected to small bell-cranks 35, which engage pins 36 fast to the pin-carrying members 25.

The pin-carrying members 25 have racks 40, at the front thereof, which engage with 90 gears 41, to thereby rotate dial-wheels 42, having indications thereon visible through a sight-opening 43. After setting the pins 24, one in each pin-carrying member, a general operator 44, having a cross-bar 45, is reciprocated by means of a handle 37 and the bar engages the pins which have been depressed to thereby carry the pin-carrying members therewith and rotate the dial-wheels 42 distances corresponding to the values of the depressed numeral-keys.

95 The general operator may be reciprocated by the handle 37, a sector 38, and pinions 39 which mesh with racks 39^a, or by means of a motor and associated mechanism, not shown. When the machine is operated by either method at a high rate of speed, the cross-bar 45 strikes the pin-bars with considerable impact and hence the dial-wheel associated therewith may be thrown ahead of the general operator, due to the one-way pawl-and-ratchet connections 48, 49, provided between each dial-wheel and each pin-bar (see Figure 3). Since the safe limit at which this machine can be operated is largely controlled by the speed at which the general operator can be moved, without overthrowing the pin-bars, there is provided interlocking mechanism for the purpose of constraining the 100 overthrow of the dial-wheel.

110 Said mechanism includes a series of locking pawls, levers or dogs 46, which are rockably mounted on a cross-shaft 47, the pawls being held in the positions shown in Figure 5 by means of springs 47^a. The forward 115 ends of the pawls 46 are provided with toes 50 designed to engage between teeth 51 of a modified gear carried by the wheels 42. All the levers 46 are simultaneously vibrated by 120 mechanism which includes a shaft 52, an arm 125

53 and a series of bail-pieces 54. The arm and the bail-pieces are secured to the shaft 52, the latter engaging hooks 55 under the pawls 46. In order that the levers 46 may be 5 vibrated during the forward stroke of the general operator while being held idle during the return stroke thereof, there is provided a one-way pawl 56 which is normally held in the position shown in Figure 5, by 10 means of a spring 57. The pawl 56 engages with a plate 58 carried by the general operator, the plate being effective to move the arm 53 upwardly when the general operator moves in the direction shown by the arrow 15 59. In Figure 6 the pawls 46 are shown in a position to prevent rotation of the wheels 42, the toes 50 being shown in the path of the teeth 51, in which position the pawls are held by the action of the arm 53, which is 20 swung upwardly when the pawl 56 is elevated by engagement with teeth 63 on the plate 58. The position of the pawls 46, shown in Figure 7, indicates the extreme position of the general operator, in which position the 25 arm 53 is swung higher by means of a tooth 60, to thereby force the toes 50 further between the teeth 51.

The return movement of the general operator is indicated by an arrow 61 in Figure 30 8. In said figure, the pawl 56 is shown riding idly over the teeth 63 of the plate 58, while the arm 53 is held in its ineffective position, by means of a spring 64. Said spring 64 is stronger than the spring 57, which is mounted 35 between spring-studs 62 and 62^a respectively secured to the pawl 56 and the arm 53. The arm 53 is held in its normal position against a pin 65 by the spring 64.

In order to synchronize the movement of 40 the pawls 46 and the wheels 42, which move relatively to the general operator, means are provided for making adjustment between the plate 58 and the general operator. Said plate has slots 69 (Figures 1 and 4) and is slidably 45 mounted on studs 66 and 70 fast to the general operator. The stud 66 carries an eccentric disk 67 designed to engage a pin 68, fast to the plate 58, so that, by rotating the eccentric disk 67, the plate may be moved relative- 50 ly to the general operator. After making the desired adjustments, the plate is locked in position by means of nuts 70^a at the ends of the studs 66 and 70.

The bail-pieces 54, which are secured to the 55 shaft 52 by means of screws 71, are not vibrated during the return stroke of the general operator. However, the levers 46 are effective to lock the wheels and prevent over-rotation thereof during the carrying of "tens" 60 into the wheels of higher denominational order. To this end, the levers 46 are provided with rearwardly-extending fingers 74, which are engaged by locking cams 75 at pre-determined positions of carrying cams 73, 65 mounted on a cross-shaft 72. It is well known

that the shaft 72 is rotated during the return movement of the general operator, being idle during the forward movement thereof. The mechanism just described is more fully disclosed in said patent to Thornton.

Since it is desired to positively lock the 70 wheels 42 when the machine stands in its normal position, and since neither the plate 58 nor the locking cams 75 are effective to swing the levers 46 to their locking positions when the general operator is in its normal or extreme rear position, there is provided a cam or roller 76, rotatably mounted upon a stud 77, carried by the general operator. Said roller engages with an arm 78, fast to the shaft 52, and is effective to rock the shaft and the bail-pieces associated therewith, and in turn swing the pawls to their effective or locking positions as shown in Figure 1.

Each dial-wheel is provided with an associated detenting pawl 79 which is held in engagement between the teeth 51 of the modified gear, to thereby position all the wheels in alignment with each other. Said pawls are held in their effective positions by means of springs 80, which may be wound around a shaft 81, upon which the pawls are pivotally mounted. The shaft 81 is secured to end plates 82, which are provided with rearwardly-extending brackets 83, upon which the 95 shaft 52 is rockably mounted.

Variations may be resorted to within the scope of the invention, and portions of the improvements may be used without others.

Having thus described my invention, I 100 claim:

1. In a typewriting and computing machine having registering devices including dial-wheels, register-bars, a pawl and ratchet drive mechanism connecting each register-bar with its dial-wheel, and a general operator therefor, the combination of a dial-wheel-controlling device vibratory throughout the rotation of the dial-wheels to prevent over-rotation thereof, the general operator being connected to simultaneously actuate the register-bars and vibrate the controlling device.

2. In a typewriting and computing machine having register-bars with pinions in mesh with said bars to rotate dial-wheels having detenting tooth-spaces, and a general operator for said bars, the combination of control-levers for engaging the tooth-spaces of the dial-wheels, and a controlling device connected to the general operator to actuate and vibrate the control-levers in and out of said tooth-spaces during the rotation of the dial-wheels, to prevent over-rotation thereof.

3. In a typewriting and computing machine having registering devices including dial-wheels, register-bars, intermediate mechanism for transmitting one-way movements from the register-bars to rotate the dial-wheels, and a general operator, the com- 125

- 5 bination of dial-wheel-controlling devices vibratory throughout the rotation of the dial-wheels to prevent over-rotation thereof, the general operator simultaneously actuating the register-bars and the controlling devices, and an adjusting device for each controlling device to adjust the same to synchronize the actuation of the controlling device with the rotation of the dial-wheels.
- 10 4. In a computing machine including a register having denominational wheels, pin-carrying members, numeral-keys for selectively setting the pins, and a general operator having a cross-bar for engaging the pins set in said pin-carrying members to rotate said wheels, the combination of means for constraining the movement of the wheels to the movement of the general operator, including an interruptive interlock with the wheels produced throughout the movement of the general operator.
- 15 5. In a computing machine including a register having toothed denominational wheels, pin-carrying members, numeral-keys for selectively setting the pins, and a general operator having a cross-bar for engaging the pins set in said pin-carrying members to rotate said wheels, the combination of means for constraining the movement of the wheels to the movement of the general operator, said means including a series of pawls engageable with the teeth of the wheels, and means movable with the general operator for imparting to said pawls a rocking movement effective to clear the teeth of said gears only as required to permit a normal movement of rotation.
- 20 6. In a computing mechanism including a register having denominational wheels, pin-carrying members for rotating said wheels, numeral-keys for selectively setting the pins on said pin-carrying members, and a general operator having a cross-bar for the pin-carrying members, to rotate said wheels, the combination of mechanism for constraining the rotation of each wheel to the movement of its associated pin-carrying member, including a pawl vibrated into interlocking engagement with each wheel throughout the movement of its pin-carrying member.
- 25 7. In a computing mechanism including a register having denominational wheels, pin-carrying members for rotating said wheels, numeral-keys for selectively setting the pins, and a general operator for the pin-carrying members, to rotate said wheels, the combination of mechanism for constraining the rotation of each wheel to the movement of its associated pin-carrying member, including a pawl, a controlling device effective to simultaneously control all the pawls, and means for operatively connecting said controlling device with the general operator in a manner to actuate the pawls in the forward stroke of the general operator, but holding the pawls
- 30 in their ineffective positions throughout the return stroke of the general operator.
- 35 8. In a computing mechanism including a register having denominational wheels, pin-carrying members, numeral-keys for selectively setting the pins on said pin-carrying members, and a general operator for the pin-carrying members, to rotate said wheels, the combination of mechanism for constraining the rotation of each wheel to the movement of its associated pin-carrying member, including a pawl, a controlling device effective to simultaneously control all the pawls, and means for operatively connecting said controlling device with the general operator in a manner to actuate the pawls in the forward stroke of the general operator, but holding the pawls in their ineffective positions during the return stroke of the general operator, said means including a rack carried by the general operator, a shaft upon which the controlling device is rockably mounted, an arm on said shaft, and a one-way pawl carried by said arm to be vibrated by the rack.
- 40 9. In a computing mechanism having toothed register-wheels, pin-carrying members for each wheel, a general operator for the pin-carrying members, a pawl-and-ratchet mechanism for operatively connecting the wheels and the pin-carrying members during the forward movement of the general operator, and detenting pawls for engaging the teeth of the wheels to align said wheels and to prevent rotation thereof during the return movement of the general operator, the combination of mechanism for preventing the wheels from running ahead of their associated pin-carrying members throughout the forward stroke of the general operator, said last-mentioned mechanism including a series of rockable locking levers and means controlled by the general operator for imparting to said levers a rocking movement effective to interlock with the teeth of said wheels in a manner to permit the escapement of only as many teeth as will correspond to the driving movement of their associated pin-carrying members.
- 45 10. In a computing mechanism having toothed denominational wheels, denominational bars associated with said wheels, and a general operator for moving the bars to rotate the wheels, the combination of means for preventing over-rotation of the wheels, said means including locking levers movable in and out between the teeth of said wheels, springs for holding the locking levers in their ineffective positions, and interruptive means carried by the general operator for continuously vibrating the locking levers to limit the speed at which the wheels may rotate.
- 50 11. In a computing mechanism having toothed denominational wheels, denominational bars associated with said wheels, and a general operator for moving the bars to ro-

- tate the wheels, the combination of means for preventing over-rotation of the wheels, said means including locking levers movable in and out between the teeth of said wheels, 5 springs for holding the locking levers in their ineffective positions, and interruptive means controlled by the general operator for vibrating the locking levers to limit the speed at which the wheels may rotate, said last-mentioned means including a plate carried by the 10 general operator, a rock-shaft having an arm fast thereto, and a trip pawl pivotally mounted on said arm, the plate having a series of cams to successively engage the pawl during the forward movement of the general operator in a manner to rock the shaft, and impart a rocking movement to the pawl between the teeth of the wheels.
12. In a computing mechanism having 15 toothed register-wheels, pin carrying members for each wheel, a general operator for the pin-carrying members, a pawl-and-ratchet mechanism for operatively connecting the wheels and the pin-carrying members during the forward movement of the general operator, and detent-pawl for engaging the teeth of the wheels to align said wheels and to prevent rotation thereof during the return movement of the general operator, the combination of mechanism for preventing the wheels from running ahead of their associated pin-carrying members during the forward stroke of the general operator, said last-mentioned mechanism including 20 a series of locking levers having interruptive movements between the teeth of said wheels, said movements being imparted to the levers by cams movable with the general operator during the forward movement thereof that become ineffective during the return movement of the general operator.
13. In a computing mechanism having toothed denominational wheels with carry-over mechanism, denominational bars associated with said wheels, and a general operator for moving the bars, to rotate the wheels, the combination of means for preventing over-rotation of the wheels, a locking lever movable in and out between the teeth of each 25 wheel, means for simultaneously vibrating all the levers between the teeth of the wheels throughout the forward movement of the general operator, and means independent of the last-mentioned means for individually 30 vibrating the levers between the teeth of the wheels during the return movement of the general operator, to thereby prevent over-rotation of the wheels upon operation of carrying mechanism.
14. In a computing mechanism having toothed denominational wheels, denominational bars associated with the wheels, and a general operator for actuating said bars, each 35 bar being operatively connected to its associated wheel by means of a ratchet and a pawl in a manner to rotate the wheels during the forward movement of the general operator, the combination of a series of locking levers controlled by the general operator throughout the forward movement thereof, for positively controlling the rotation of the wheels preventing over-rotation thereof, said means including a rock-shaft having a universal member fast thereto, said member being connected with the locking levers in a manner to vibrate the levers in and out between the teeth of said wheels, and means for operatively connecting said rock-shaft with the general operator in a manner to rock the shaft only during the forward movement of the general operator.
15. In a computing mechanism having toothed denominational wheels, denominational bars associated with the wheels, and a general operator for actuating said bars, each bar being operatively connected to its associated wheel by means of a ratchet and a pawl in a manner to rotate the wheels during the forward movement of the general operator, the combination of a series of locking levers engageable with the teeth of said wheels, interlocking means vibrated by the general operator throughout the forward movement thereof, for controlling the rotation of the wheels and preventing over-rotation thereof, and means for positively locking all the wheels when the general operator reaches its full forward stroke.
16. In a computing machine having a series of registering wheels, a general operator connectible for rotating said wheels selectively miscellaneous distances, and individual locking dogs for said wheels, said wheels having toothed or notched portions to co-operate with said locking dogs, the combination with said wheels, of mechanism dependent upon the forward movement of the general operator to prevent overthrow of each wheel, said mechanism including a rack on the general operator having motion-conveying toothed spacings timed to the unit-spacings of the registering wheels.
17. In a computing machine having a series of registering wheels, a general operator connectible for rotating said wheels selectively miscellaneous distances, and individual locking dogs for said wheels, said wheels having toothed or notched portions to co-operate with said locking dogs; the combination with said wheels, of mechanism dependent upon the forward movement of the general operator for preventing overthrow of each wheel, said mechanism including a rack on the general operator having motion-conveying toothed spacings timed to the unit-spacings of the registering wheels, and a pawl engageable by the teeth of the rack and operatively connected to convey a step-by-step wheel-locking movement throughout the forward movement of the general operator.

18. In a computing machine having a series of normally locked registering wheels, and a general operator connectible for rotating said wheels individually through predetermined unit distances of one to nine, the combination with the wheels, of mechanism dependent upon the movement of the general operator and effective to first release the wheels and then successively lock the wheels during each subsequent accumulation of single units to prevent the overthrow of individual wheels.

19. In a computing machine having a series of normally locked registering wheels, and a general operator connectible for rotating said wheels individually through predetermined unit distances of one to nine, the combination with the wheels, of mechanism dependent upon the movement of the general operator and effective to first release the wheels and then successively lock the wheels during each subsequent accumulation of single units to prevent the overthrow of individual wheels, said mechanism including a wheel-locking rack effective during the movement of the general operator in one direction to temporarily lock all the wheels and a wheel-locking cam effective during the return movement of the general operator to permanently lock all the wheels.

20. In a computing machine having a series of registering wheels normally locked to prevent idle rotation, and a general operator connectible for rotating said wheels computatively through predetermined units of distance, the combination with the wheels, of mechanism dependent upon the continuous forward movement of the general operator in registering a succession of units, to release and relock the wheels during the registry of each unit to prevent overthrow of the wheels.

21. In a computing machine, having a series of registering wheels normally locked to prevent idle rotation, and a general operator connectible for rotating said wheels computatively through predetermined units of distance, the combination of mechanism dependent upon the continuous forward movement of the general operator in registering a succession of units, to release and relock the wheels during the registry of each unit to prevent overthrow of the wheels, said mechanism including a rack on each wheel and individual rack-locking pawls vibrated by the general operator during each unit of its travel to successively release and lock the racks.

OTTO THIEME.
